CYLINDER CONTROLLING MECHANISM

Joseph Wawzonek, Central Falls, R. I., assignor to
 Hemphill Company, Central Falls, R. I., a corporation of Massachusetts

Application June 25, 1948, Serial No. 35,232

3 Claims. (Cl. 66—14)

1

This invention relates to a mechanism for controlling the cylinder of a circular, independent needle, knitting machine of the type having superposed co-axial needle cylinders. It relates particularly to the upper cylinder.

Since the needles of such a machine are transferable from one cylinder to the other, it is advisable that the adjacent ends of the cylinders be as close together as possible. The possible closeness of fixed cylinders depends upon the nature of the equipment of the machine and may vary from, say, $\frac{1}{4}$ " to $\frac{3}{4}$ ". Departure from a minimum closeness decreases the certainty of proper needle transfer and increases the probability of defective knitting and machine difficulties.

One of the reasons for the limited capabilities of two cylinder machines is the inadvisability of separating the cylinders enough to permit the use of wrap and other mechanisms of the types in use on single cylinder machines such as the well known Banner type of machines, for example. By this invention the advantage of closely spaced cylinders for rib knitting and transferring and extremely widely spaced cylinders for lower cylinder work are made available automatically while the machine is running.

One form of the invention is shown in the drawings of which:

Fig. 1 is an elevation showing the two cylinders and part of the controlling mechanism of the upper cylinder.

Fig. 2 is a similar plan view; and

Figs. 3, 4 and 5 are views of other parts of the controlling mechanism of the upper cylinder.

As shown in Fig. 1, lower cylinder 1 may be of conventional type and mounting. Upper cylinder 2 may also be generally conventional but departs from the conventional adjacent its upper end above the needle slots where it is provided with longitudinal splines or keys 3 equally spaced about and projecting from the cylinder and adapted to slide within slots 4 in ring gear 5 by which the cylinder is driven and which otherwise may be of conventional design.

Integral with or affixed to upper cylinder 2 is an extension 6 provided with a circumferential channel 7 within which are positioned opposed rollers 8 and 9 (Fig. 2) rotatably mounted on the respective ends of a yoke 10. Yoke 10 constitutes one end of a lever 11 which is pivoted between its ends as at 12 so as to be swingable in a vertical plane. It will be evident that by operating lever 11 cylinder 2 can be raised or lowered at will without disconnecting it from its driving gear 5

2

since splines 3 are not withdrawable from slots 4 but move always within the slots and that the separation of the two cylinders can be varied at will within relatively wide limits while the machine is in operation.

The controlling mechanism shown consists of rollers 8 and 9, yoke 10 and lever 11 already mentioned and operating connections 13 and 14, the latter of which is pivoted at 15 and is provided at 10 its free end with a roller 16 which is engageable with a cam or cams such as 17 on a drum 18. This specific mechanism is, of course, only illustrative.

This is all that is required for raising and lowering the upper cylinder 2 at any desired time and to an extent sufficient for all practical requirements. Sufficient, for example, to entirely free the needles from any association with the upper cylinder when they are operating exclusively in 20 the lower cylinder or to permit the use of a wrap spindle requiring a space between cylinders of three inches or more and on the other hand to bring the cylinders as close together as practical while knitting rib or transferring needles.

25 In short, any impediment heretofore resulting from the relative positions of the cylinders is eliminated completely for all practical purposes.

The controlling mechanism described above may be supplemented as desired by a locking device which opposes any undesired movement. This is shown in Figs. 3-6, particularly in Fig. 5. It consists of a rocker 19 pivoted at 15 and adapted to be raised by a cam 20 offset from cam 17 on drum 18. Rocker 19 has a tail 21. A lever 30 22 pivoted at 22a overhangs the free end of lever 14 where it is provided with a screw 23 as an adjustable operating connection. The other end of lever 22 terminates in a hook 24 which by adjustment of screw 23 can be made to bear upon the tail 21 of rocker 19. Cams 17 and 20 may be proportioned and positioned and the adjustment of screw 23 may be such that whenever roller 16 on lever 14 is resting upon drum, lever 19 is 35 upon the drum, roller 16 is upon cam 17. Also, when roller 16 is moving up to or down from the top of cam 17, lever 19 is moving down from or up to the top of cam 20. Therefore, the movements of the cylinder are positively restricted to 40 those produced by cam 20 and those movements are positively assured.

So that the jacks or sliders of the upper cylinder may not be displaced when the upper cylinder is raised, the cams which operate them should be retractable and should be retracted when the 45 50

cylinder is being raised or lowered. There should also be a levelling cam operative before the cylinder is raised to bring all jacks and sliders to common levels which cam may also function again when the cylinder is returned to its previous position to insure that these levels have been maintained before the jack or slider cams are made operative again.

I claim:

1. For a circular, independent needle, knitting machine having a cylinder and means for rotating it, a cylinder controlling device which includes means for raising and lowering said cylinder and means for insuring positive operation of said raising means, said raising means including a drum, a cam thereon, a rocker adapted to ride upon the surface of said drum and said cam and connections between said rocker and said cylinder whereby the rocking of said rocker is translated into vertical movements of said cylinder, said insuring means including another cam on said drum, another rocker adapted to ride upon the surface of said drum and of said other cam in opposition to the movements of said first men-

tioned rocker and means operatively connecting the two rockers.

5 2. For a circular, independent needle, knitting machine, a controlling device as claimed in claim 1 in which the means operatively connecting the two rockers is adjustable.

10 3. For a circular, independent needle, knitting machine, a cylinder controlling device as claimed in claim 1 in which the means operatively connecting the two rockers translates the rocking of one rocker in one direction into rocking of the other rocker in the other direction.

JOSEPH WAWZONEK.
